UNITED STATES PATENT OFFICE.

ALMA MORGAN DAVIS, OF MESA, ARIZONA.

TRACTOR.

1,267,986.

Specification of Letters Patent. Patented May 28, 1918.

Application filed December 7, 1917. Serial No. 206,008.

To all whom it may concern:

Be it known that I, ALMA MORGAN DAVIS, a citizen of the United States, and a resident of Mesa, in the county of Maricopa and State of Arizona, have invented a new and Improved Tractor, of which the following is a full, clear, and exact description.

This invention relates to tractors, and particularly to an improved power structure therefor, and has for an object the provision of an improved structure which will operate for moving in either direction, while allowing the master propelling member to move continuously in the same direction.

Another object in view is to provide a tractor in which earth engaging members are provided and connected up with a prime mover so as to push or pull a load.

A further object of the invention is to provide a tractor with earth engaging members and a reverse mechanism for reversing the earth engaging members without reversing the engine driving same.

In the accompanying drawings:

Figure 1 is a longitudinal vertical section through a device embodying the invention, same being taken approximately on line 1—1 of Fig. 7.

Fig. 2 is a view similar to Fig. 1 showing the parts in a different position.

Fig. 3 is a view similar to Fig. 2 except that the same shows the parts at the end of the power stroke.

Fig. 4 is a view similar to Fig. 1 except that the parts are shown in their inactive or return position.

Fig. 5 is a view similar to Fig. 1, but showing the parts in their reversed position.

Fig. 6 is a view similar to Fig. 5 showing the parts at the beginning of the power stroke in a reversed position.

Fig. 7 is a transverse sectional view through Fig. 1 on line 7—7.

Fig. 8 is a view similar to Fig. 1, but showing a double contact member, certain parts being eliminated.

Referring to the accompanying drawings by numerals, 1 indicates a suitable frame, 2 supporting wheels. Connected with the frame 1 are a plurality of guides 3 as shown in Figs. 1 and 7 guiding the slides 4. It is evident that any desired number of slides and associate parts may be used without departing from the spirit of the invention. Connected with each slide 4 are contact shoes 5 and 6, shoe 5 acting as the ordinary

forward propelling member, while shoe 6 acts as a reverse power member. Shoe 5 is connected to the slide 4 by links 7 and 8 pivotally connected to the shoe and to the slide, 60 while the shoe 6 is pivotally connected to slide 4 by links 9 and 10. Each of the shoes is divided centrally and hinged together so as to conform to the shape of the ground. A power link 11 is pivotally connected at 12 65 to the slide 4 and at 13 to the crank 14. Crank 14 is formed integral with, or rigidly secured to a shaft 15, which shaft is supported on frame 1 and is driven by engine 16 through any suitable means as for instance 70 the beveled gears 17 (Fig. 7). A link 18 is pivotally connected with the crank 14 at 13 and also pivotally connected at 19 to the crank 20, which crank is driven by engine 16. The use of the crank 20 is to raise the 75 shoe 5 when returning the parts from the full stroke position as shown in Fig. 3 to the beginning of the stroke as shown in Fig. 1.

In Fig. 4 will be seen the intermediate 80 position of parts wherein it will be seen that the shoe 5 is lifted during its return trip as the cranks 14 and 20 move from the position shown in Fig. 4 to that shown in Fig. 1, and slide 4 on the shoe 5 moves forwardly 85 and the shoe also moves downwardly until it contacts with the ground, after which it remains in contact with the ground while power is exerted on the slide 4 and the shoe to urge the shaft 15, frame 1 and associate 90 parts forwardly. A cable, chain, or other supporting member 21 is slack during the power stroke, but acts for raising the shoe during the return stroke. A cable, chain, or other member 22 is connected with shoe 5 95 and a cable 23 is connected with shoe 6 and also to the end 24 of the bell crank 25 and near the center of the lever 27 as shown in Fig. 5. When these levers are as shown in Fig. 1 the device is driving forwardly, but 100 when the lever is moved to a vertical position, as shown in Fig. 5, cable 22 will raise permanently the shoe 5 and cable 23 will be slack so that the shoe may fall by gravity to the earth, or be forced against the earth by a 105 spring or other means. As the crank 14 continues to rotate this will cause a reverse movement of the vehicle without reversing the motive power. The power stroke of the crank 14 in forward motion is the lower half 110 of the revolution of crank 14 as in Fig. 2. The return stroke of crank 14 is the upper

half of its revolution as shown in Fig. 4 and the shoes 5 and 6 have the positions shown in Figs. 5 and 6 when the machine is in reverse motion. It will be seen that in order for the cable 28 to properly perform the function of raising the shoe 6 at the end of the power stroke and lowering shoe 6 at the beginning of the power stroke in the reverse it is necessary for cable 28 to be attached to a crank opposed to crank 14 which may be on the same shaft or another. It will thus be seen that when the parts are moving forwardly the lever and associate parts are as shown in Fig. 1 and to reverse the direction of movement of the vehicle a forward movement of lever 27 to a vertical position is all that is necessary, whereupon the vehicle will begin to move in the opposite direction, though the power member continues to operate in the same direction. On each of the shoes 5 and 6 spurs may be provided for causing a better gripping action of the shoes when the device is in use. The parts are intended to operate for pulling or pushing and may be used with sleds, vehicles having wheels, or other devices to be moved, but is preferably used where a comparatively slow progress is all that is required, but considerable power.

In Fig. 8 will be seen a slightly modified form of the invention, in which the power shaft 14' is connected to links 29 and 30 which links engage slides 31 and 32 arranged with guide 33 whereby there will be a propelling shoe near the front and near the rear of the frame 1 of the vehicle. It is evident that two propelling means may be used, or a large number without departing from the spirit of the invention.

What I claim is:

1. A tractor of the character described, comprising a body, supporting members for supporting said body, a guideway connected with said body, a slide guided by said guideway, a traction shoe connected with said slide by a parallel link motion, a power

member arranged in said body, means for connecting the power member with the slide for causing the slide to reciprocate, and means operated by the power member for raising said shoe when said slide is moving in one direction.

2. A tractor of the character described, comprising a body, supporting members therefor, a plurality of slides supported by said body, a pair of traction shoes for each slide, each of said traction shoes being connected with the respective slides by a parallel link motion, power means for reciprocating said slides, means for raising said shoes during the travel of said slide in one direction, and means for maintaining one of said shoes in an elevated position during the movement of said slide whereby the device may be propelled in either direction.

3. A tractor of the character described, comprising a body, supporting means for supporting said body, a plurality of pairs of guides supported by said body and extending longitudinally thereof, a slide supported and guided by each pair of guides, a pair of shoes for each slide, a plurality of links connecting said shoes with said guides, said links being arranged to produce a parallel motion, a connecting rod pivotally connected with each of said slides, a crank connected with each of said connecting rods, a power member for rotating said cranks thereby reciprocating said slides, means operated by said power member for maintaining one of said shoes connected with each slide in an elevated position, said means being capable of reversing so that either shoe may be brought in contact with the ground at any time and the device propelled in either direction without reversing the direction of movement of said cranks, and means for raising said shoes from the ground at the completion of each power stroke thereof.

ALMA MORGAN DAVIS.
